UNITED STATES PATENT OFFICE.

JOHN HARRISON, OF EAST POINT, KENTUCKY.

PLOW.

SPECIFICATION forming part of Letters Patent No. 618,088, dated January 24, 1899.

Application filed June 16, 1898. Serial No. 683,603. (No model.)

To all whom it may concern:

Be it known that I, JOHN HARRISON, a citizen of the United States, residing at East Point, in the county of Johnson and State of Kentucky, have invented a new and useful Plow, of which the following is a specification.

The invention relates to improvements in plows.

The object of the present invention is to improve the construction of double plows and to provide a simple, strong, and inexpensive one in which the shorter beam may be readily shifted from one side to the other of the longer beam to reverse the plow.

15 A further object of the invention is to provide a simple and efficient locking device for securing the shifting beam at either side of the plow and to enable the said shifting beam to be readily removed when it is desired to 20 change the plow from a double plow to a single plow.

The invention consists in the construction and novel combination and arrangement of parts hereinafter fully described, illustrated 25 in the accompanying drawings, and pointed out in the claims hereto appended.

In the drawings, Figure 1 is a perspective view of a plow constructed in accordance with this invention. Fig. 2 is a transverse sectional view, the shifting beam being arranged 30 at one side in full lines and at the other side in dotted lines. Fig. 3 is a detail perspective view of the coupling for connecting the front end of the shifting plow-beam to the main or fixed beam. Fig. 4 is a detail perspective 35 view of the locking-lever and its ends or bolts. Fig. 5 is a detail perspective view of the guide for the locking pins or bolts.

Like numerals of reference designate corresponding parts in all the figures of the drawings.

1 designates a main or fixed beam, and 2 a shifting or reversible beam which is adapted to swing downward and laterally of the main 45 beam to carry it from one side of the plow to the other side thereof for reversing the plow to enable the advance or front shovel to be arranged at either side of the same. The rear ends of both beams are curved downward and 50 extended forward slightly to form arms, which are adapted to receive suitable shovels or similar cultivating devices.

The front end of the fixed or main beam is bent into the form of a hook 3 to form a clevis, and it is provided at the shank of the hook 55 or clevis with a rearwardly-extending perforated ear 4, located beneath the front portion of the beam and spaced therefrom to receive the front portion of a coupling 5. The front portion of the coupling 5 is horizontal and is 60 perforated for the reception of a vertical bolt 6, which passes through the ear 4 and a perforation of the beam 1. The rear portion of the coupling is bifurcated, and the sides formed by the bifurcation are vertical and receive 65 between them the front end of the shifting beam 2, which is pivoted to the rear portion of the coupling by a horizontal bolt 7. By this construction of coupling the reversible beam 2 is adapted to swing downward and 70 moves laterally of the plow to carry it from one side to the other.

The rear portion of the beam 2 is connected with the rear portion of the main beam 1 by an oscillating transversely-disposed brace 8, 75 provided at the ends with eyes 9 and 10, which are linked into slots or openings 11 and 12 of the beams 1 and 2, whereby the ends of the brace are hinged to the beams. The eyes 9 and 10 are formed by substantially U-shaped 80 straps 13 and 14, detachably secured to the body of the brace by bolts, which permit the brace to be readily removed, and by removing the bolt 7 at the front end of the shifting beam 2 the latter can be taken off when it is 85 desired to arrange the parts for forming a single plow.

The outer end of the oscillating brace 8 is provided with oppositely-disposed stops 15, projecting from the upper and lower faces of 90 the brace when the latter is arranged in a horizontal position and preferably formed by a plate oppositely tapered, as shown. The ends of the plate are arranged to support the shifting beam and are arranged at the inner 95 face of the same.

The shifting beam is locked at either side of the main beam by means of a pair of reciprocating pins or bolts 16, located at opposite sides of the main plow-beam and arranged 100 to engage perforations 17 of a plate 18 of the oscillating brace. The plate 18 of the oscillating brace is similar in form to the outer plate, which forms the stops 15, and is swung

from one side of the main beam to the other, being contiguous to the same. The reciprocating pins or bolts which engage the inner plate of the oscillating brace are guided in openings or eyes 19 of a support 20, which is mounted upon the main beam between the oscillating brace and a pair of inclined braces 21, that support the handle-bars 22. The support 20 consists of a longitudinal body or shank and a clip 23, arranged at and depending from the front end of the body or shank and embracing the main beam directly in rear of the opening or slot 11. The clip is provided with a clip-plate, and the locking pins or bolts, which are located at each side of the main plow-beam, are reciprocated by an operating-lever 24, located between the handle-bars and having its lower end forked or bifurcated to receive the shank or body of the support 20. The forked or bifurcated portion of the lever is fulcrumed near the lower end, and the portions beyond the fulcrum or pivot 25 are pivoted to the rear ends of the locking pins or bolts. The support is provided at its rear end with oppositely-disposed stops 26, which limit the forward swing of the upper portion of the operating-lever by being arranged in rear of the lower portion in position to be engaged by the same, and they prevent the locking pins or bolts from being withdrawn from the guide eyes or openings of the support.

When it is desired to change the shifting beam from one side of the main beam to the other, the operating-lever is swung forward and the handle-bars lifted, which causes the shifting beam to swing downward and laterally of the plow, which is lowered after the oscillating brace has moved past the center.

40 The bolts or pins are moved forward into engagement with the plate of the shifting beam when the operating-lever is released by a curved or bowed spring 28, mounted on the main plow-beam and engaging the lower portion of the operating-lever, and a pair of springs may be employed, if desired, and they can be mounted in any othersuitable manner.

45 The handle-bars, which are arranged in the usual manner, incline upward and rearward, being secured at their lower ends to opposite sides of the main plow-beam, and they are supported by the braces 21, which are provided at their upper ends with perforations 29 for the reception of the bolts 30 and to enable the plow-beam 1 to be adjusted relative to the handle-bars to cause the plow to run deep or shallow. The handle-bars are connected near their upper or rear ends by a transverse bar, and the said upper or rear 50 ends are shaped into handles, as shown.

55 The invention has the following advantages: The double plow, which is simple, inexpensive, strong, and durable, is adapted to be readily reversed to bring the front shovel at either side of it, and the shifting beam may be readily removed when it is desired to form a single plow. The reversible or shifting

beam is firmly supported in both of its positions, and the locking mechanism is easily operated to release and engage the oscillating brace.

70 Changes in the form, proportion, and minor details of construction may be resorted to without departing from the spirit or sacrificing any of the advantages of this invention.

75 What I claim is—

1. A reversible plow comprising a main or fixed beam, a reversible or shifting beam connected at its front end with the main beam by a coupling adapted to permit it to swing vertically and horizontally to carry beneath the main or fixed beam, and a brace connecting the beams and hinged to the same and adapted to swing laterally of the plow, substantially as and for the purpose described.

80 2. A plow comprising a main or fixed beam, a reversible or shifting beam connected at its front end to the main beam and diverging therefrom, an oscillating brace connecting the beams and hinged at its ends to the same, whereby the shifting beam is adapted to swing downward and laterally of the plow to change it from one side to the other of the same, and means for locking the shifting beam at the sides of the main beam, substantially as described.

85 3. A plow comprising a main beam, a coupling arranged at the front of the main beam and provided with pivots arranged at right angles to each other, one of the pivots connecting the coupling with the main beam, a shifting beam connected with the other pivot and adapted to swing downward beneath the main beam from one side of the plow to the other, and means for locking it in either position, substantially as described.

90 4. A plow comprising a main beam, a shifting beam movably connected at its front end to the main beam, an oscillating brace hinged at its ends to the beams and disposed transversely of the plow, stops located at the ends of the transverse brace and projecting above and below the same, and a locking device for engaging the stops at the inner end of the brace, substantially as described.

95 5. A plow comprising a main beam, a shifting beam arranged to swing beneath the main beam from one side of the plow to the other, a transverse brace connecting the beams and hinged to the same, stops projecting from the upper and lower faces of the transverse brace and provided with perforations, a pair of locking bolts or pins located at opposite sides of the main beam and arranged to engage the perforations of the stops, and a forked operating-lever connected with the pins or bolts and adapted to reciprocate the same, substantially as described.

100 6. A plow comprising a main beam, a shifting beam adapted to swing beneath the plow from one side to the other, a transverse connection hinged to the beams and provided with perforated stops projecting from its top and bottom, a support mounted upon the

main beam and provided with a clip for embracing the same, said clip having perforations at opposite sides, bolts guided in the perforations and arranged to engage the stops, 5 a forked lever fulcrumed on the support, and means for limiting the movement of the bolts, substantially as described.

In testimony that I claim the foregoing as my own I have hereto affixed my signature in the presence of two witnesses.

JOHN HARRISON.
